Attorneys

UNITED STATES PATENT OFFICE.

VICTOR KALINOWSKI, OF SOUTH CHICAGO, ILLINOIS.

BRUSH.

Application filed August 2, 1924. Serial No. 729,803.

To all whom it may concern:

Be it known that I, VICTOR KALINOWSKI, a citizen of Poland, residing at South Chicago, county of Cook, and State of Illinois, have invented certain new and useful Improvements in a Brush, of which the following is a specification.

My present invention relates to brushes, and more particularly to brushes, especially well adapted for use in cleaning pots or the like.

The primary object of the invention is to provide an improved brush embodying features whereby the brush head may be disposed in various positions with respect to the handle of the brush.

A further object of the invention is to provide an improved brush embodying features whereby should the brush head become worn so as to render it unfit for further use, the same may be readily removed and a new one substituted therefor upon the original handle of the brush.

A still further object is in the novel construction of the brush whereby a material saving of wood will be had, since the handle portion of the brush which is preferably made of metal, may be readily associated with the wooden brush head block, thereby eliminating the use of the usual wooden handle portion which, since it constitutes a portion of the brush head, must be discarded when the brush becomes worn out.

Other objects and advantages of the invention will be apparent during the course of the following detailed description, taken in connection with the accompanying drawing, forming a part of this specification and in which drawing:-

40 Figure 1 is a perspective view of a brush constructed in accordance with my invention;

Fig. 2 is a central longitudinal section through the same and showing the brush head in a reversed position after the forward bristles have become worn;

Fig. 3 is a sectional view taken on the line 3—3 of Figure 2, looking in the direction of the arrows;

50 Fig. 4 is a sectional view taken on line 4—4 of Figure 3, looking in the direction of the arrows; and

Fig. 5 is a bottom plan view of the improved brush head block showing the general appearance thereof before the bristles have been secured thereto.

Referring to the drawing in detail, and wherein similar reference characters designate corresponding parts throughout the several views, the letter A may generally designate my improved brush comprising a handle portion B; a brush head C, and means D for retaining the brush head C in adjusted relation to the handle portion B.

Referring to the handle portion B, which is preferably formed from sheet metal, the same embodies a handle 10 which may be formed by rolling the metal into tubular formation, and at the forward end of which is formed a substantially flat square head 70 plate 11 having depending side plates 12 formed at its longitudinal edges. These side plates 12 are bent inwardly at a point intermediate their upper and lower edges for providing inwardly extending tongues 75 or guides 13 which extend longitudinally throughout the entire length of the side plates. The rear end of each side plate 12 has a portion bent inwardly at right angles to the side plates, for forming stops 14 80 which are adapted to limit the inward movement of the brush head C when being positioned in the handle portion B.

The brush head C comprises a head 15 which is preferably square shaped in plan, and to the substantially convexed bottom face 16 of which divergently arranged bristles 17 are attached in any suitable manner desired. Each of the four side walls 18 of the head 15, which are preferably of a 85 height equal to that of the side plates 12, are provided intermediate their upper and lower marginal edges with longitudinally extending grooves 19 which communicate one with another at the marginal end portions of the side walls. The top face 20 of the head 15 is flat in order that when the brush head C is positioned in the handle portion B, the top face of the head will lie in surface contact with the lower face of the flat head plate 11 for reinforcing the same and also permitting of the proper functioning of the retaining means D with respect to the brush head C.

Referring to the means D for retaining the brush head C in adjusted relation upon the handle portion B, the same preferably consists of a thumb screw 21 having its screw threaded shank 22, which is adapted to be threaded downwardly through the 100 head plate 11, extending into a coaxially disposed recess 23 provided in the upper

face 20 of the head 15. Owing to the relatively thin sheet metal of which the handle portion may be constructed, a nut or bearing block 24 having a screw threaded bore, 5 is preferably welded or otherwise secured coaxially of the outer face of the head plate 11 for providing a substantial bearing for the shank of the thumb screw.

During the use of the ordinary type of 10 brush for cleaning pots or the like, the forwardly inclined bristles of the brush head become worn very short, while the rear bristles of the brush show little or no wear.

When these forward bristles become worn 15 to an appreciable degree, the brush is ordinarily discarded because of the fact that it is impossible to use the brush for effectively cleaning in the corners of the pots or pans.

20 By so constructing the brush as disclosed, an arrangement will be had whereby four different positions of the brush head may be had with respect to the handle of the brush, thereby permitting the unworn bristles of the brush head to be disposed in a forwardly inclined position with respect to 25 the handle portion. This is clearly illustrated in Figure 2 of the drawing. This construction not only permits of the entire

30 using up of the bristles of the brush head, but also permits of a new brush head to be readily associated with the original handle portion of the brush.

35 After the forwardly inclined bristles of the brush head have become worn to an extent where they cannot be forced into the corners of a pot for thoroughly cleaning the same, the thumb screw 21 may be turned free of the recess 23, for permitting of the 40 brush head to be drawn forwardly out of the handle portion B. The brush head may then be turned to the desired position and slid back into the handle portion with the longest bristles foremost of the brush. 45 Since the head 15 is square shaped in plan, and has the grooves 19 provided in each side wall thereof, it can be seen that the brush head may be slid into the handle portion in any one of four positions. The stops 50 14 serve as means for aligning the recess 23 in a position for receiving the shank of the thumb screw 21 which is adapted to be turned into the recess for preventing withdrawal of the brush head from the handle portion of the brush.

55 From the foregoing description of this invention, it is obvious that a brush has been provided embodying novel features of construction, and possessing practical merit, in that the same will permit of the entire

using up of the bristles of the brush, due to the arrangement whereby the brush head may be disposed at various positions with respect to the handle portion.

Various changes in the shape, size and 65 arrangement of parts may be made to the form of the invention herein shown and described, without departing from the spirit of the invention or the scope of the claims.

I claim:

1. A brush comprising a handle, a head plate at one end of said handle, having depending side walls formed at the longitudinal edges thereof and provided intermediate their upper and lower edges with inwardly extending guides extending longitudinally throughout the length of the side walls, a removable and reversible brush head comprising a head portion having a face and side walls and bristles extending from said face, each of said side walls being provided with longitudinally extending grooves for sliding interfitting relation with said guides of the head plate, and means for retaining the brush head in the head plate and in the desired adjusted relation with respect to said handle.

2. A brush comprising a handle, a head plate at one end thereof having depending side walls formed at the longitudinal side edges thereof and provided with inwardly struck guides extending longitudinally throughout the length of the side walls, a removable brush head for the head plate embodying a head portion being square shaped in plan and having a centrally disposed recess provided in the upper face thereof and with each of the four side walls of said head provided with longitudinally extending grooves extending throughout the length of the walls, bristles extending from said head, and a set screw threaded downwardly through said head plate and adapted to have the shank portion thereof turned into the recess in the upper face of said head whereby the brush head will be retained in adjusted relation with said handle.

3. As an article of manufacture, a brush head comprising a head portion being square shaped in plan and formed with a flat upper face, straight side walls, and a convex bottom face, each of said side walls being provided intermediate the upper and lower margins thereof with longitudinally extending grooves communicating one with another at the corner junctures of the side walls, and bristles extending in diverging relation from the convexed bottom face of the head.

VICTOR KALINOWSKI.
